CLAIM

The ornamental design for a seat, as shown and described.

DESCRIPTION

FIG. 1 is a front perspective view of the seat showing my new design;

FIG. 2 is a right side elevational view, the left side view being a mirror image thereof; and

FIG. 3 is a front perspective view of a second embodiment of the seat.

The left side view is a mirror image of FIG. 2. The rear view is generally unornamented.

FIG. 1.

FIG. 2.

FIG. 3.
